The ornamental design for a collapsible vehicle step bar, as shown and described.

DESCRIPTION

FIG. 1 is a side elevational view of a collapsible vehicle step bar showing my new design.

FIG. 2 is an exploded top plan view thereof, showing a separate center section having a right end and a left end, a separate right telescoping section and a separate left telescoping section;

FIG. 3 is a top plan view thereof shown with the right telescoping section partially inserted into the right end of the center section, and the left telescoping section partially inserted into the left end of the center section. The bottom plan view being a mirror image;

FIG. 4 is a top plan view thereof shown with the right telescoping section and the left telescoping section fully inserted into the respective end of the center section;

FIG. 5 is a front elevational view thereof;

FIG. 6 is a rear elevational view thereof; and,

FIG. 7 is a right side elevational view thereof; the left side being a mirror image.

In the drawings, the broken lines depict a vehicle and form no part of the claimed design.
